UNITED STATES PATENT OFFICE.

EUGENE R. MATTESON AND WILLIAM J. HUTCHINS, OF JOLIET, ILLINOIS,
ASSIGNORS TO WILLIAM H. HUNTER AND ROSE E. MATTESON, BOTH
OF SAME PLACE.

WIRE-BARBING MACHINE.

SPECIFICATION forming part of Letters Patent No. 313,090, dated March 3, 1885.

Application filed October 13, 1884. (No model.)

To all whom it may concern:

Be it known that we, EUGENE R. MATTESON and WILLIAM J. HUTCHINS, citizens of the United States of America, residing at Joliet, 5 in the county of Will and State of Illinois, have invented certain new and useful Improvements in Wire-Barbing Machines, of which the following is a specification, reference being had therein to the accompanying drawings.

Figure 1 is a side elevation; Fig. 2, a plan view on the top. Fig. 3 is a cross-sectional view of Fig. 1 on line 1, looking toward the rear of the machine, designed to more clearly show the barb-wire feed with relation to the cutting-off dies or shears and the barb-grasping and holding jaws; Fig. 4, a view on the outer end of one of the strand-wire coilers, showing the mechanism by means of which the coilers are prevented from rotating backward. Fig. 5 is a perspective view of the cam-wheel L^4 at the front end of the machine, which cam operates and governs the movements of the reciprocating barb grasping and holding jaws, causing said jaws to grasp enough barb-wire 25 to form a barb, move forward with it and hold it until the strand-wires are coiled on it by the strand-wire coilers, then release it and recede; Fig. 6, a view on the inner end of one of the coiler-shafts, showing the pawl-and-ratchet 30 mechanism, by means of which said coiler-shaft is caused to rotate in one direction only. Fig. 7 is a cross-sectional view of Fig. 1 on about line 2, designed to more clearly show the strand-wire coilers and the mechanism by 35 means of which they are operated. Fig. 8 is a plan view on the top of the inner ends of the two strand-wire coilers, and a horizontal cross-sectional view of the upper barb-grasping jaw, designed to more clearly show the 40 precise manner in which the coilers coil the strand-wires around the barb. Fig. 9 is a perspective view of the reciprocating head H detached from the machine, showing the barb-grasping and holding jaws P^3 and P^4 attached 45 thereto, designed to show the construction and arrangement of these parts. Fig. 10 is an edge view of a portion of the barb grasping and holding jaws P^3 and P^4 , showing how their faces are formed to press a crimp in the mid-

dle of the barb. Fig. 11 is a plan view of that portion of the machine called the "take-up," 50 to take up the finished barbed wire, and for compressing the strand-wires properly on the barb. Fig. 12 is a bottom plan view of that part of the machine called the "strand-wire 55 compressor," which, after the strand-wires are coiled on the barb, compresses the two coils toward each other on the barb. Fig. 13 is an end view of said strand-wire compressor; and Figs. 14 and 15 are perspective views of 60 the finished barbed wire, it being the product of the machine.

The invention in this case consists in a machine for making barbed fence-wire, and is designed to automatically attach a pair of 65 strand-wires to the barbs, consisting of short pieces of wire pointed at each end and crimped in the center by coiling the two strand-wires on said barbs—one on either side of the crimp 70 in the barb—either in the same or in opposite directions from each other, as may be desired, thus coiling the strand-wires on the barbs to hold them on, instead of coiling the barbs on the strand-wires, as has usually and invariably been the case where wire barbs are 75 used, forming what is termed a "two-strand two-pointed" wire barb.

Referring to the drawings, A represents the main frame or bed of the machine mounted on suitable legs, A' , at each corner. The hanger-boxes E^2 E^3 are attached to one side of the bed A to support the drive-shaft S . On this drive-shaft S is located the sprocket-wheel P , which drives the machine by means of a sprocket-chain from the power. (Not necessary to be 85 shown.) There are also keyed to shaft S the miter-gears B^4 B^5 , that respectively mesh with the miter-gears B^3 B' , keyed on the counter-shafts S' S^2 , to drive them, and also the cam 90 L^4 , that operates lever L to reciprocate the sliding plate L^2 , that operates the toggles, to cause the jaws P^3 P^4 to grasp the barb.

To the rear end of shaft S is keyed the cog-wheel G , which, through the medium of idler cog-wheel G' and cog-wheel G^2 , drives 95 the twister T , which is of the ordinary pattern and forms no part of this invention.

Counter-shaft S' is attached to the bed A by

means of hanger-boxes, as shown in Figs. 1 and 3, and has keyed to it the two cams G^3 G^3 , of the form shown in Fig. 1, having cam-channels of the form shown by the dotted lines in said figure. These two cams drive the coiling-shafts c c , which are located across the top of the machine in suitable boxes, as shown in Figs. 1, 2, and 7, through the medium of the two oscillating arms, c^3 c^3 , keyed on the rock-shaft S^3 , boxed to the cross-bars A^2 of the machine, as shown in Figs. 1 and 7: The roller-wrists U' U' on the sides of these oscillating arms c^3 travel, respectively, in the cam-channels of the cams G^3 G^3 , and when said cams rotate, the form of their channels causes the said arms to oscillate back and forth at their upper ends, where they are provided with the toothed segments c^2 c^2 for engaging with the cog-teeth c' , forming an integral part of the head e , by means of which said head e and cog-wheel c' are rotated first in one direction and then in the other once around, according to the oscillations of said arm and segment. The head e and cog-teeth c' integral therewith are sleeved on over the coiling-shaft c , and are held thereon between the box of said coiling-shaft and its integral ratchet-teeth t' . (Shown in Fig. 6.) The two coiling-shafts c c and their driving mechanism are duplicates, so that a description of one will suffice for both. The said head e is provided on its inner surface, between it and its coiling-shaft, with a series of spring-pawl, t . (Shown in Fig. 6.) These pawls t and ratchet-teeth t' cause the coiling-shafts to rotate intermittently in one direction once around. The rear ends of the coiling-shafts c are provided with annular collars m , held thereon by means of set-bolts m' , (shown in Fig. 7,) to hold them in their respective boxes. The heads of these set-bolts m' project, as shown in Figs. 4 and 7, so the pawl m^2 , engaging with it, will prevent the backward turn of said coiling-shafts. The front ends of the coiling-shafts c c are located to stand directly opposite to each other as far apart as the bars are long, and are each provided on their facing ends with the nipples n n , located at one side from the center of the coiling-shafts, from which nipples the strand-wires w w emerge through proper holes running longitudinally through the coiling-shafts, as shown, for the purpose of carrying the strand-wires out far enough to coil them on the barb near its center, and leave room between the ends of the coilers for the barb while the strands w are being coiled on it, as shown in Figs. 2, 7, and 8. The strand-wires pass into the machine through these coiling-shafts, one from each side, as shown in said figures, and are by them coiled on the barb in the manner and form shown particularly in Figs. 7, 8, 14, and 15, as will be more particularly set forth herein-after. The counter-shaft S^1 is attached to the bed A by means of proper hanger-boxes, as shown in Fig. 1, and has keyed to it the miter

gear-wheel B³, cam-wheel G⁴, and eccentric y. Cam-wheel G⁴ reciprocates the sliding head H, (shown in Figs. 1, 3, and 9,) through the medium of oscillating arm c' and link P². Arm c' is boxed on shaft S³, as shown in Fig. 1, and is provided with a roller-wrist on its side, as shown by the dotted lines in said figure, that travels in the cam-channel on the side of cam-wheel G⁴. The upper end of arm c' is connected by means of link P² with the reciprocating-head H, as shown in Figs. 1 and 9. When cam-wheel G⁴ rotates, it will, by means of such connection with head H, reciprocate it back and forth in proper guideways on the bed A and in frame B'', attached to bed A, as shown in Figs. 1, 2, and 3. This reciprocating head is for the purpose of supporting and carrying the barb grasping and holding jaws P³ and P⁴. Looking at Fig. 9, the lower jaw, P⁴, is shown as attached permanently to the lower part of sliding head H, while the upper jaw, P³, is shown as attached permanently to the outer end of arm D², the inner end of which pivots to the side of head H near its inner end, for the purpose of permitting said jaws to be opened and closed to grasp a barb, carry it forward to a point opposite the center of the coiling-shafts c c, and hold it firmly while the strand-wires are being coiled on it. The wire w' of which the barb is formed is fed in the machine from one side between a pair of feed-rollers, v v', of the ordinary pawl-and-ratchet pattern, driven to rotate intermittently from shaft S'. This feed is shown particularly in Figs. 1, 2, and 3. The feed-rollers v v' are keyed to shafts that have cog-wheels keyed to their opposite ends to drive both feed-rollers at the same velocity. The shaft of roller v has a ratchet-wheel keyed on it at about the center, as shown in Fig. 1, and an arm, R⁶, boxed on it, to the side of which a spring-pawl is pivoted to engage with said ratchet. To the outer end of arm R⁶ is pivoted the connecting-rod R¹, (shown in Fig. 3,) which forks over shaft S', as shown in Figs. 1 and 3, between a collar on the outer end of said shaft, to prevent it from falling off, and a face-wheel, R⁵, having a wrist-pin, R³, to engage with the lug R² on said connecting-rod, so that when face-wheel R⁵ rotates, it will reciprocate connecting-rod vertically, and thus by means of said ratchet rotate said feed-rollers intermittently in the same direction to feed the barb-wire in between them, the length of stroke being regulated by means of the slot in the outer end of arm R⁶. (Shown in Fig. 3.) The barb-wire passes from between these feed-rollers v v', first through the guide-tube w², as shown in Figs. 2 and 3, thence between the cutting off dies in heads E z, and is delivered between the jaws P³ P⁴, and of sufficient length to make a barb. At the instant enough wire w' is so fed in between the said jaws for a barb, the sliding plate L² (shown in Fig. 1) begins to move forward by means of its connection with cam L⁴ on the end of shaft S, through the medium of the arm L, pivoted on the machine

on bracket L³, and the link L'. This sliding plate is provided with the toggles a and a' and the flanges a², to back up and assist in operating said toggles. The upper ends of toggles 5 a pivot to the side of frame B², and their lower slotted ends to the side of said sliding plate, by means of proper screw-bolts. The toggles a' pivot at their upper ends to the side of sliding plate L² by means of proper screw-bolts, while 10 their lower ends hang down loosely to rest on the upper surface of the bar D, which in turn rests and rides on roller D'. The bar D is loose, but held in place by means of the screw-bolt b³ passing down loosely through 15 the overhanging upper end of standard H', and screwed firmly into said bar D, so it can have vertical movement to a certain extent. A pair of side plates, B', prevent said bar D from falling outsidewise. The forward movement 20 of said sliding plate L² will cause said toggles to depress said bar D down on roller D', and thus cause jaws P³ P⁴ to close and firmly grasp the barb, and by the form of their faces, as shown in Fig. 10, crimp it, as shown in said 25 figure. The sliding head H then begins to move forward by means of its said connection with cam G⁴, and as soon as it has so started forward, the cutting-off dies in the heads E z sever the barb b loose diagonally, to leave it 30 pointed, so it can be carried forward by the jaws P³ P⁴ to the coiling-shafts c c. The barb is then carried forward by said jaws until its points are between and opposite the centers of the two coiling-shafts c c, and are held firmly 35 until the said coiling-shafts rotate with the two strand-wires to coil each one around the extending prods of the barb on either side of said jaws, one on either side of the central crimp in the barb, as is shown in Figs. 7, 8, 14, 15. 40 The form of cam L⁴ then causes sliding plate L² to recede, which opens the toggles a a' and relieves bar D from pressure, which permits the jaws P³ P⁴ to open by means of the upward pressure of spring M on the under side of arm 45 D². (Shown in Fig. 9.) This causes said jaws to release their grasp on the barb, which requires their service no longer, as it is then held within the coils of the two strand-wires. At the instant the barb is so released the sliding head H moves 50 back to its original position ready for another like operation. The two strand-wires are thus each coiled around the barb once, one on either side of the central crimp in it, to form such a barb as is shown in Figs. 14 and 15. The 55 strand-wires may each be coiled on the barb in the same direction, as shown in Fig. 14, or in opposite directions, as shown in Fig. 15. The only change necessary in the machine would be to reverse one of the cams G³ on shaft 60 S', which would cause the arms c³ to be reciprocated in opposite directions. The lower cutting-off die is secured in the head E of the machine, as shown in Figs. 1, 2, 3. The upper cutting-die is secured in the head z of the oscillating arm z'. (Shown in said figures.) Said oscillating-arm z' is pivoted, as shown in Fig. 65 2, on the upper face of standard-head E, and

is caused to oscillate by means of the cam F² on shaft S, through the medium of oscillating arm F pivoted to the side of the bed A, as 70 shown in Fig. 3. Cam-wheel P² on shaft S in its revolution impinges against the lower end of arm F and causes it to oscillate, and by that means through the medium of link F', oscillates arm z' for the purpose of causing the 75 said cutting-off dies to sever the barb loose, as stated. A coil-spring attached to the outer end of arm z' returns it, as shown in Fig. 2. There is nothing particularly new in the cutting-off dies or their operating parts or mechanism, and any suitable mechanism for cutting off the barb may be used instead of the one shown. After the strand-wires have been thus coiled on a barb, they must be drawn along through the machine far enough, so the 80 next succeeding barb can be attached in like manner. This is accomplished by that portion of the machine denominated the "take-up." (Shown in Figs. 1, 2, and 11.) Looking at said figures, J² are a pair of parallel 85 guideways attached to the machine, as shown in Fig. 1, on the bed J¹, forming a part of the standard H' and on the standard K⁴, both said standards standing on and bolted to the bed A, as shown in Fig. 1. These guideways are 90 95 of the form shown in cross-section in Fig. 13.

K is a reciprocating head which reciprocates in the grooves of and between said guideways by means of the eccentric y on shaft S², through the medium of oscillating arm K³, boxed on shaft S⁴, link K², and lugs K', as 100 shown in Fig. 1. A pair of barb-guides, J', are secured permanently to the upper surface of reciprocating head K, and are of the same form in cross-section, as shown at J in Fig. 13, having the longitudinal grooves e' for the prods of the barbs to travel in. On the upper side of one of these guides J' is attached an integral standard, to the side of which is pivoted a spring-pawl, J⁵, (shown in Figs. 1 and 2,) which pawl is located so as to hang down and rest on the strand-wires between 105 said barb-guides J'. These barbed strand-wires come from the barbing part of the machine and pass to the twister T through between 110 these guides J', the prods of the barbs traveling in the grooves e' and the strand-wires between them. As the eccentric y reciprocates the head K, each move toward the twister will draw the barbed wire along the required distance to place the next succeeding barb in the strand-wires by means of the spring-pawl closing on the strand-wires to hold it firm on the head K, so that the reciprocation of the said head K intermittently draws the barbed strand-wires along out of the machine to the spooler 115 and twister T. When the strand-wires are first coiled on the barb, the coils or loops in them are left by the coilers spread apart to some extent and not near enough the center of 120 the barb on account of the jaws P³ P⁴ being in the way.

It is necessary before the barbed wire leaves the machine to compress the two coils of the

two strand-wires toward each other to the center of the barb, so that they may be in close contact with each other. In order to accomplish this, the strand-wires after they are 5 coiled on the barb are first drawn between a pair of compressing-jaws, J, that are adapted to open and close on them, so as to compress the coils, as aforesaid. These jaws are shown at J in Fig. 11, and an end view in Fig. 13. 10 They are located on the upper surface of the fixed head K, which is held firmly between the guides J² at the end toward the coilers, as shown in Fig. 11, and are pivotally attached thereto, as shown in said figure, so that their 15 ends toward the coilers may open and close, and they are provided on their under sides with integral lugs or pins r'. (Shown by the dotted lines in Fig. 11 and on the bottom in Fig. 12.) These lugs pass down through the 20 slot r in head K⁵, and extend below the bottom of said head through the slots r² in the reciprocating plate J³, which is attached, as shown in Fig. 11, to the under side of reciprocating head K, and is caused to reciprocate by means of its attachment to head K. 25

Fig. 12 is a plan view on the bottom of reciprocating plate J³ to show its form, and to show its slots r² with the lugs r' of jaws J passing through them. As the plate J³ reciprocates by means of its attachment to head K, it will, by means of said lugs r' passing through its slots r², open and close the jaws J. When head K is nearest head K⁵, the lugs r' will be 30 in the eccentric portion of said slots, and thereby open the jaws J, as shown in Fig. 11. These jaws are provided with the longitudinal grooves e', as shown in Fig. 13, for the barb-prods to travel in. When head K reciprocates toward the twister T, it will draw on 35 plate J³, and cause it, by means of the slots r² and lugs r', to close said jaws J up against the sides of the coils of the strand-wires on the barb, and compress them toward each other toward the center of the barb to leave the finished barbed wire in the forms shown in Figs. 40 45 and 15.

Having thus described our invention, what we claim as new, and desire to secure by Letters Patent, is as follows, to wit:

50 1. In the wire-barbing machine described, the combination of the strand-wire coiling-shafts e e, each having strand-wire apertures passing through their length at one side from their center out through the nipples n n, the 55 integral ratchet-teeth t, toothed heads e, spring-pawls t and m², and lugs m', with the segment-racks e³ and cams G³ G³, as and for the purpose set forth.

2. In a wire-barbing machine, the means 60 described and shown for holding a barb while it is being severed from the barbing-wire, the means described for conveying a barb from the cutters to the strand-wire coilers, and the

means described for holding the barb between the strand-wire coilers while the strand-wires 65 are being coiled around the barb, substantially as and for the purpose set forth.

3. In the wire-barbing machine described, the combination of the cam L⁴, lever L³, link L', sliding plate L², toggles a a', bar D, arm 70 D², having the roller D', spring M, sliding head H, and jaws P³ P⁴, with the cutting-dies in heads E and z, feed-rolls v v', and the means, substantially as shown and described, for operating said parts, as and for the purpose set 75 forth.

4. In the wire-barbing machine described, the combination of the reciprocating heads K and K⁵, having the barb-guides J' J' and jaws J J, respectively, slotted plate J³, studs r', 80 dog J⁵, link K², arm K³, and eccentric y, as and for the purpose set forth.

5. In a wire-barbing machine, the combination of the mechanism described for holding the barb, with the mechanism described 85 for coiling the strand-wires around the barb, substantially as and for the purpose set forth.

6. In a wire-barbing machine, the combination of the means for intermittently feeding forward the barbing-wire between a pair of 90 corrugated reciprocating jaws, means for closing said jaws upon the barb to crimp its center, means for severing the barb from the barbing-wire while it is held between said jaws, means for operating said jaws while they are 95 holding a barb to convey it from the barb-wire feed to and between a pair of oppositely-located strand-wire coilers, means for intermittently rotating said strand-wire coilers to coil a pair of strand-wires, as described, around 100 the barb, one on either side of its central crimp, means for operating said jaws to release the barb when it is within the coils of the strand-wires and for returning them to their former position while they are open, and means for intermittently taking up the strand-wires as they are supplied with barbs by pulling them through the apertures in the strand-wire coilers, so that barbs may be placed on said strand-wires at suitable distances apart, as set forth.

7. In a wire-barbing machine, the means, substantially as shown and described, for closing the barb-grasping jaw P⁵ on a barb, to hold it while it is being conveyed from the 115 cutters to the coilers, for releasing the barb after the strand-wires have been coiled around it, and for holding the barb-grasping jaws open until they are returned to the feed and cutters and receive another barb, as set forth. 120
